UNITED STATES PATENT OFFICE.

LUDWIG J. ROEHR, OF NEWARK, NEW JERSEY, ASSIGNOR TO THE BASSETT JEWELRY CO., OF NEW YORK, N. Y.

DESIGN FOR A LOCKET.

SPECIFICATION forming part of Design No. 22,074, dated December 20, 1892.

Application filed October 22, 1892. Serial No. 449,701. Term of patent 3½ years.

To all whom it may concern:

Be it known that I, LUDWIG J. ROEHR, a citizen of the United States, and a resident of the city of Newark, in the county of Essex and State of New Jersey, have invented and produced a new and original Design for Lockets, of which the following is a specification, reference being had to the accompanying drawings, illustrating the same.

- 10 In the drawings Figure 1 is a front face or obverse view of a locket having a design in accordance with my invention. Fig. 2 is a view of the opposite or reverse side of the locket, showing the design for the back of the same.
- 15 The distinguishing characteristics of my design reside in the peculiar ornamentation of the face or lid and back or body of the locket, all as represented in the accompanying drawings.
- 20 Referring to Fig. 1 *a* denotes a raised bead running around the edge of the locket, and *b* indicates a circle of short radial lines, constituting a ring of milling just inside of the circumferential beading. In the plain, flat, central space circumscribed by this milled ring is struck up, in what is known as low relief, a representation, as *c*, of the main exhibition building of the Columbian Exposition, decorated with flags and streamers. To the left

of the building is a curved row of lamp or torch bearing pillars *f*, arranged around the edge of a sea wall *g* extending clear across the picture. In the foreground a water scene or lake view is pictured, as at *h*, with various small craft afloat thereon.

Referring to Fig. 2, *a* is the raised circumferential beading, and *b* the annular milled ring, as on the obverse or front face shown in Fig. 1. The circular space inclosed by the ring on this side of the locket is ornamented as at *d* by a medallion, also in low relief, of the discoverer of America, the face being beardless, and wearing a hat, the rim being cocked or bent up at each side of the head. The edge or periphery of the locket is to be hatched or milled, as indicated at *e* in the edge views under Figs. 1 and 2.

Having thus described my design, what I claim and desire to secure by Letters Patent is:—

The design for a locket, substantially as herein illustrated and described.

In testimony whereof I hereunto affix my signature in the presence of two witnesses.

LUDWIG J. ROEHR.
